UNITED STATES PATENT OFFICE.

HOMER D. MARTINDALE, OF MIDDLETOWN, OHIO, ASSIGNOR, BY MESNE ASSIGNMENTS, TO THE BLACK-CLAWSON COMPANY, OF HAMILTON, OHIO, A CORPORATION OF OHIO.

JORDAN-ENGINE-SHELL LINING.

Application filed April 13, 1925. Serial No. 22,567.

This invention relates to Jordan engine shell linings.

The objects attained in my invention consist in a shell lining which is assembled as a unit before the same is introduced into the shell of the engine; which can be assembled where it is made, shipped as a unit to where it is to be used, and installed intact, thus saving greatly in time and costs involved in the more common practice of assembling the linings piece by piece in the shells.

To this end, I provide in the practice of my invention a metal jacket approximating in shape and size the inner conformation of the shell to be lined, the general shape of the jacket being conical, in which the metal fly bars, or blades, and the spacing bars are adapted to be assembled in the relation the same are to sustain one to another in the shell, thus forming a complete lining unit which is adapted to fit free in the shell, fixed relation of the lining with the shell being then effected by expanding the lining unit.

In the accompanying drawings:

Figs. 1, 2 and 3 are sectional views of my improved shell linings, illustrating the relative sizes of several units which are commonly used to a shell;

Fig. 2 is a detail cross-sectional view of a lining unit as introduced in the shell;

Fig. 3 is a detail cross-sectional view of a lining unit as expanded in the shell;

Figs. 4 and 5 are detail views illustrating suitable joints for the metal lining jackets;

Fig. 6 is a detail view of a wood spacing bar;

Fig. 7 is a detail view of a blade;

Fig. 8 is a detail view of the lining expanding bar.

My invention is here shown in a form applicable to the common type of Jordan engines, a showing of the complete apparatus being unnecessary to an understanding of the invention.

The metal jacket 1 of each lining unit, as illustrated in Figs. 1, 2 and 3, is formed of suitable gauge metal, the shape being conical to conform to the interior shape of the shell, the shape of the jacket as formed being maintained by an expandible joint, as shown at 2 in Fig. 4 or 3 in Fig. 5, the nature and purpose of the expandible joint being presently described.

The blades 4 and spacing bars 5 are then

assembled in the metal jacket and are held in place in the jacket by a longitudinally tapered or wedge-shaped expansion bar 6 which is driven between two opposite spacing bars 5, as shown in Figs. 2 and 3, to complete the annular shape of the lining and to expand the same in the jacket to hold the parts in fixed relation one with another with sufficient firmness to maintain the unit intact for shipping and handling incident to installing the lining in the Jordan.

Installing of the linings is a very simple matter,—the units being introduced endwise in the Jordan shell 7, and the expanding bar 6 driven home to force spreading of the joint 2 or 3, thus resulting in further expansion of the lining to assume fixed relation with the shell by the outward pressure of the parts thereon, the relation of the parts being shown in Fig. 3.

The jacket joint 2, shown in Fig. 4, illustrates a suitable brazed joint which will yield under expansion pressure exerted on the jacket by the wedging action. The joint 3, shown in Fig. 5, illustrates a common form of spot welding suitable to the practice of the invention, the joint being adapted to yield and spread under the expanding action of assembling the lining in the Jordan.

Any suitable means, as conical-shaped cores, adapted to be arranged inside the conical jackets with suitable space between the core and jacket, may be employed to facilitate assembling of the blades and spacing bars in the jackets, the use of such means being illustrated in one form in Fig. 2, the core being illustrated as part 8.

Having described my invention, I claim:

1. A shell lining for a Jordan engine including in combination, an expandible jacket shaped to conform to an inner section of the shell and having a yieldable joint adapted normally to prevent expansion of said jacket, a plurality of blades and blade spacing elements adapted to be assembled and expanded in said jacket in its normal relation to effect a shell lining unit, and means operable after said unit is introduced in a shell to spread the joint and expand the lining unit to effect fixed relation between the unit and said shell.

2. A shell lining for a Jordan engine comprising an expandible holding means shaped to conform with an inner section of the shell

and having a rupturable joint adapted normally to prevent expansion of said holding means, a plurality of blades and blade spacing elements held in said holding means in its normal relation, the rupturable joint in said holding means being adapted to be broken so that the joint may be spread upon expansion of the assembled blades and blade spacing elements after the lining has been introduced in a shell, to effect fixed relation between the lining and the shell.

3. A shell lining for a Jordan engine comprising an expandible jacket of thin sheet material shaped to conform to an inner section of the shell and having a rupturable joint adapted normally to prevent expansion of said jacket, a plurality of blades and blade spacing elements wedged tightly in place in said jacket in its normal relation to effect a shell lining unit capable of being inserted and expanded within the shell, and means operable after said unit is introduced into the shell to rupture the joint and expand the lining unit to effect fixed relation between the unit and the shell.

4. A shell lining for a Jordan engine comprising an expandible sheet metal jacket shaped to conform with an inner section of

the shell and having a welded joint connection capable of being ruptured but adapted normally to prevent expansion of the jacket, a plurality of blades and blade spacing elements assembled and expanded in said jacket in its normal relation to effect a shell lining unit, and a wedge operable after the unit is introduced into a shell to rupture the welded connection and expand the lining unit to effect fixed relation between the unit and the shell.

5. For use in the shell of a Jordan engine, a series of blades and blade spacing elements arranged in alternate relation into a pre-formed shell lining adapted to be inserted, expanded and maintained within the Jordan shell, and means for holding said blades and blade spacing elements is preformed relationship as a complete filler unit comprising a part periphery enclosing said blades and blade spacing elements and extending completely around the same and having a rupturable joint adapted to be broken upon expansion of the blades and blade spacing elements after the lining is in place within the shell.

In testimony whereof I affix my signature.
HOMER D. MARTINDALE.
